UNITED STATES PATENT OFFICE.

CHARLES H. SHAW, OF TROY, ASSIGNOR TO WILLIAM S. EARL AND GARDNER EARL, OF SAME PLACE, AND WASHINGTON WILSON, OF NEW YORK, N. Y.

BUTTON-HOLE FOR CUFFS, &c.

SPECIFICATION forming part of Letters Patent No. 234,620, dated November 16, 1880.

Application filed January 22, 1880.

To all whom it may concern:

Be it known that I, CHARLES H. SHAW, of Troy, in the county of Rensselaer and State of New York, have invented certain new and 5 useful Improvements in Button-Holes for Cuffs and other Articles, of which the following is a specification.

My invention relates more particularly to button-holes for cuffs, collars, and other laundry-dried articles; and it consists in embossing the material along the sides of the button-hole in such way as to render it flexible and easier to bend aside in the insertion and removal of a stud or button, also to enhance the appearance 15 of the button-hole.

In the accompanying drawings, Figure 1 is a perspective view of a cuff embodying my invention, showing material surrounding its button-hole embossed in different ways; and 20 Fig. 2 is a section of the same, taken at the plane of the dotted line $x x$, Fig. 1.

Similar letters of reference designate corresponding parts in both figures.

The cuff A may be of any desirable shape 25 or style and material—such, for instance, as linen; and the button-hole may be of the usual straight shape, oversewed and stayed at the ends by cross-sewing or cross-barring, if desirable. The material adjacent to the button-holes (but, as shown, opposite the sides only of the said button-holes) is embossed or deflected out of line with the rest of the cuff. As shown, a semi-ellipsoidal portion, B, is thus embossed or deflected along each side of 30 the button-hole, forming, as it were, flaps on each side of the button-holes. These flaps B are, owing to their deflection from the body of the cuff, quite flexible. Hence they may be more easily bent aside in inserting or removing 35 a stud or button than the sides of an ordinary button-hole.

In connection with most of the button-holes, the flaps or portions adjacent to the button-holes are both embossed or deflected outward; but in connection with one of the button-holes I have shown one flap or portion, B, embossed or deflected outward and the opposite flap or portion, B', embossed or deflected in-

ward. The latter may afford the greater facility for inserting or removing a stud or button, and hence may prove the more desirable, but it is perhaps less ornamental.

Not only are button-holes with the adjacent material more easy to use and more ornamental in appearance than those of the ordinary kind, but they are thought to have advantages in interlocking the opposite edge portions of the cuff together when properly overflapped and to preserve a better relation between them. Moreover, the embossed portions or flaps fill up the space between the front and back of a stud better, and hence hold it more effectually in its proper position.

The embossing or deflecting of the material adjacent to the button-hole may be done in various styles, so as to produce various ornamental designs. If such material be embossed or deflected into corrugations the flaps of a bellows-body construction will be produced, and such flaps will be very flexible, and consequently afford very great facility for the insertion and removal of a stud or button.

Any of the flaps or embossed portions may, to facilitate the insertion of a stud or button, be wetted with the tongue or otherwise to increase their flexibility, and without wetting the cuffs.

The embossing or deflecting may be done with dies or otherwise subsequent to the laundrying and starching, but before the cuffs dry; or the cuffs may be allowed to dry and may be remoistened and embossed or deflected in any suitable manner.

If desirable, the moist starch or other stiffening agent may be expressed by means of porous or perforated dies, or partially or wholly destroyed by an acid or otherwise, to render the embossed or deflected material more flexible.

Laundrying or other machines of simple construction suitable for embossing or deflecting the material adjacent to the button-holes may be furnished the purchasers or users of cuffs or other articles at little cost.

While only illustrated in connection with the button-holes of cuffs, my invention is ap-

licable to collars, shirts, and various other articles with good results.

What I claim as my invention, and desire to secure by Letters Patent, is—

- 5 1. A button-hole having the material along its sides embossed or deflected, substantially as and for the purpose specified.
2. A button-hole having the material along

its sides embossed or deflected in the shape of semi-ellipsoidal flaps extending from end to end of the button-hole, substantially as and for the purpose specified.

CHAS. H. SHAW.
